UNITED STATES PATENT OFFICE.

OLE SEVERIN LIED, OF CHRISTIANIA, NORWAY.

IGNITING AND EXTINGUISHING DEVICE FOR GAS-BURNERS.

No. 856,534.

Specification of Letters Patent.

Patented June 11, 1907.

Application filed January 2, 1907. Serial No. 350,495.

To all whom it may concern:

Be it known that I, OLE SEVERIN LIED, 5
inspector, a citizen of Norway, residing at
Eugeniegade 20, Christiania, Norway, have
invented new and useful Improvements in
Igniting and Extinguishing Devices for gas-
burners, of which the following is a specific-
cation.

My invention relates to that class of gas
burners in which gas jets are ignited and ex-
tinguished by causing the pressure in the gas-
supply pipe to rise for a short time and then
again to fall, whereby a bell, a piston, a dia-
phragm or the like is moved in order to feed
15 forward a ratched wheel which causes the
supply valve of the gas-jet to open or close
thereby igniting or extinguishing the jet.

My present invention has for its object to
provide an igniting and extinguishing device
20 of a simple construction and safe operation
and also one which may be easily inspected
and repaired without dismounting other
parts than those of the mechanism itself.

In order to enable the invention to be fully
25 understood I will describe the same by refer-
ence to the accompanying drawing.

—1—is the gas supply pipe through which
the gas passes by the channel —2—, by-pas-
sage —3—, chamber —4—, and pipe —5—
30 to the pilot light, which burns at a suitable
height in the burner —6—, the gas supply
through the orifice —7— to the main jet be-
ing closed as long as the valve —8— rests on
its seat —9—, drawn downwardly by the
35 weight of the valve stem —10—.

Above the pipe —1— is located a dia-
phragm —11— loaded by plates —12— or
other weights. The said diaphragm is pro-
vided with a central stem —13—, which is
40 guided in the strap —14— and the upper
end of which projects into a freely accessible
chamber —15—. In this chamber is ar-
ranged the ratchet wheel —16— provided
with projections or cams —17—. The stem
45 —13— has on its upper end a pivoted pawl
—18—, which engages with the wheel —16—.

The chamber —4— is closed at its lower
end by a flexible diaphragm —19—, connect-
50 ed to the lower part of the valve stem —10—,
which at its lower and upper parts is con-
trolled by fixed guides —21— and —22—
and which stem carries at its lower end a
roller —23— resting on the periphery of the
cam wheel —17—.

55 The pipe —5— is attached to a piece
—24— screwed fast to and projecting into

the chamber —4—. Said piece has a pas-
sage —25— connecting pipe —5— with the
interior of chamber —4—. Said passage
ends inwardly in a seat —26— for a valve 60
—27— forming a part of a lever —28— piv-
oted to a lug —29— on the piece —26—.
The tail —30— of said lever is operated by a
stopper —31— clamped around the valve
stem —10—. The wheels —16, 17— are 65
carried by a bracket —32— attached to the
band —33—, which in combination with the
pipe —3— form the support of the chamber
—4—. Said bracket —32— is integral with
the guiding strap —14— and is provided with 70
a detaining spring —34— meshing with the
ratchet wheel —16—.

In order to prevent dust etc, from enter-
ing the chamber —15— this latter is sur-
rounded by a loose cap —35— preferably of 75
brass.

The operation of the mechanism is as fol-
lows: As soon as the pressure in the gas sup-
ply pipe is increased, the diaphragm —11—
is lifted, and causes the pawl —18— of the 80
stem —13— to turn the ratchet wheel —16—
one tooth forward, so that the top of one of
the cams —17— is moved beneath the roller
—23— secured to the valve stem —10—.
The valve —8— is thereby slowly raised, 85
thus admitting the gas to the main burner,
and the pilot light ignites the main jet. The
pilot light will then be extinguished, the
tail —30— being released from the stopper
—31—, whereby the valve —27— under in- 90
fluence of its own weight is moved down
to its seat —26— in order to cut off the gas
supply to the pipe —5—. The pressure is
then again lowered, whereby the diaphragm
—11— together with the stem —13—, is 95
lowered to its normal position, and the pawl
—18— engages with the following tooth,
the ratchet wheel —16— not being oper-
ated. If the main jet is to be extinguished
and the pilot light ignited the pressure in 100
the supply pipe is again increased and then
lowered, so that the ratchet wheel is moved
forward one tooth more and the roller —23—
passes into the depression between two of
the cam surfaces —17—, the valve —8— be- 105
ing closed at the same time as the gas is ad-
mitted to the pipe —5—, whereby the main
jet after having ignited the pilot light is ex-
tinguished. The parts will then be in the
position shown on the drawing.

110
It will be seen, that the single pin of the
mechanism operating on the ratchet wheel

is the pivot pin of the pawl —18— and all the parts, which are required to be examined and adjusted viz: the parts —18, 16, 17 and 23— are located in the easily accessible chamber —15—.

Having now particularly described and ascertained the nature of my said invention and in what manner the same is to be performed I declare that what I claim is:

- 10 1. In an igniting and extinguishing device for gas burners, a casing provided with a flexible diaphragm, a stem provided with a pawl and secured to said diaphragm and a wheel having ratchet teeth for engagement by said pawl and having peripheral curved projections less in number than said ratchet teeth, in combination with a main valve for opening and closing an orifice leading to a main jet, and a stem connected with said valve and provided with a part engaged by the aforesaid peripheral curved projections of the ratchet wheel.
- 15 2. In an igniting and extinguishing device for gas burners, a casing provided with a flexible diaphragm, a pawl and ratchet mechanism operatively connected with said diaphragm and a wheel connected with said ratchet and having peripheral curved projections less in number than the teeth of said ratchet, in combination with a main valve for opening and closing an orifice leading to a main jet, and a stem connected with said valve and provided with a part engaged by the aforesaid peripheral projections of the
- 20 3. In an igniting and extinguishing device for gas burners, a casing having a chamber
- 25
- 30
- 35

open to atmosphere and with upper and lower flexible diaphragms, a ratchet wheel in said chamber and having peripheral curved projections less in number than the teeth of said wheel, a pawl, carried by the lower diaphragm referred to, for engagement with the ratchet wheel, and a main valve for opening and closing an orifice leading to a main jet, said valve connected with the upper diaphragm and in operative relation with said wheel.

4. In an igniting and extinguishing device for gas burners, a casing having a chamber open to atmosphere and with upper and lower flexible diaphragms, a ratchet wheel in said chamber and having peripheral curved projections less in number than the teeth of said wheel, a pawl, carried by the lower diaphragm referred to, for engagement with the ratchet wheel, a closed chamber constantly supplied with gas, a main valve for opening and closing an orifice from said closed chamber to a main burner, a second valve for opening and closing an orifice from said chamber to a pilot burner, and a stem connected with the upper diaphragm referred to, and in operative relation with said wheel, for operating both of said valves.

In testimony whereof I have signed my name to this specification in the presence of two subscribing witnesses.

OLE SEVERIN LIED.
